UNITED STATES PATENT OFFICE.

THOMAS JOSEPH GORMAN, OF LAMPMAN, SASKATCHEWAN, CANADA.

MAIL-BAG CATCHING AND DELIVERING APPARATUS.

1,155,911.

Specification of Letters Patent.

Patented Oct. 5, 1915.

Application filed May 26, 1914. Serial No. 841,128.

To all whom it may concern:

Be it known that I, THOMAS J. GORMAN, a citizen of Canada, residing at Lampman, in the Province of Saskatchewan and Dominion of Canada, have invented new and useful Improvements in Mail-Bag Catching and Delivering Apparatus, of which the following is a specification.

The invention relates to a mail bag catching and delivering apparatus.

The primary object of the invention is the provision of an apparatus of this character wherein the mail bags are exchanged between a moving train and a station so that the mail bags can be automatically handled without requiring any slackness in the speed of travel of the train at stations throughout its route, thereby permitting the trains to maintain an accurate schedule.

Another object of the invention is the provision of an apparatus of this character wherein the mail bags will be positively caught and delivered between the train and station without the possibility of their loss, or damage to the same.

A further object of the invention is the provision of an apparatus of this character which is simple in construction, reliable and efficient in its operation, and inexpensive in manufacture and installation.

Other objects will be in part obvious and in part hereinafter pointed out.

The invention accordingly consists in the construction, combination of elements and arrangement of parts which will be exemplified in the construction hereinafter set forth, and the scope of the application of which will be indicated in the appended claims.

In the drawings:—Figure 1 is a top plan view showing a car approaching a station with the devices of the apparatus constructed in accordance with the invention in relative positions with respect to each other. Fig. 2 is a side elevation thereof. Fig. 3 is a sectional view on the line 3—3 of Fig. 1. Fig. 4 is a front elevation. Fig. 5 is a sectional view on the line 5—5 of Fig. 1.

Similar reference characters indicate corresponding parts throughout the several views in the drawings.

Referring to the drawings in detail, A designates a mail car, which is of the ordinary well-known construction, B the doorway in the side thereof, through which projects the car mail bag catching and delivery device C, while D designates the station mail

bag catching and delivery device, both being hereinafter fully described.

The car device C comprises a pair of spaced parallel supporting bolsters or beams 10 which are mounted in the car A to project through the doorway B therein beyond the side of the said car. Secured to the bolsters or beams 10 are spaced vertically disposed substantially inverted U-shaped inner and outer uprights 11 and 12 respectively, while arranged between the said uprights are a series of spaced brackets 13 which are fixed transversely to the beams or bolsters 10 and form stands for spaced pairs or horizontally disposed inner and outer mail bag catching and delivery rails 14 and 15 respectively, the latter rails being connected to substantially L-shaped hangers 16 which are fixed in the uprights 11 and 12 to reinforce and brace the same, while fixed to the inner rails 14 in alignment with the hangers are vertical grab arms 17 formed at their upper ends with reversely extended hooks 18, the rails 14 and 15 being parallel and disposed in spaced relation to each other. At the ends of the rails 15 are upwardly divergent tapered tips 19, while fixed to the under sides of the said rails are downwardly directed outwardly tapered auxiliary tips 20 which latter are adapted to co-operate with the station device D in a manner hereinafter described.

Secured to the uprights 11 and 12 and to the outer rails 15 are side guards 21 which serve to prevent the falling of the mail bags from the rails 14 and 15 when caught thereon, or when being delivered therefrom.

The inner rails 14 are formed with beveled ends 22 to assure the proper co-operation of the station device therewith.

The station device D comprises a support or upright 23, which is suitably anchored within the ground at a station, and is formed with out-turned extensions 24 at its upper end, and to these extensions are fixed spaced suspension brackets 25 carrying horizontally disposed spaced parallel mail bag catching and delivery rails 26 which are arranged in series, three in number, each rail being formed with downwardly inclined outwardly tapered tips 27 which are adapted to engage the beveled ends 22 of the rails 14 so as to be guided between the said rails 14 and rails 15 to deliver a mail bag thereonto and to catch a mail bag therefrom. The mail bag to be delivered from the station device D to

the device C is positioned at one side of the suspension brackets 25, while the mail bag caught from the said device C by the station device D is deposited at the opposite sides of the brackets 25 on the latter. This operation is similarly carried out with respect to the bag delivered to the car device and the bag caught by the station device D when the train passes a station while at full speed. 10 The auxiliary tips 20 on the car device C serve to guide the tapered tips 27 of the station device therebetween to aline both devices for the positive exchange of mail matter between a station and a moving train.

15 What is claimed is:—

1. A mail bag catching and delivering apparatus comprising a car supported element having spaced vertically disposed inverted U-shaped inner and outer uprights, spaced brackets arranged between the uprights, horizontally arranged rails on the brackets and having outwardly divergent tapered ends, hangers rising from the intermediate brackets, a stationary element having a horizontal arm provided with spaced depending hangers, horizontally arranged rails movable between the first-named hangers slightly above the plane of the first-named rails and having inclined tapered ends.

movable between the first-named hangers slightly above the plane of the first-named rails and having inclined tapered ends. 30 2. A mail bag catching and delivering apparatus comprising a car supported element having spaced vertically disposed inverted U-shaped inner and outer uprights, spaced brackets arranged between the uprights, horizontally arranged rails on the brackets 35 and having outwardly divergent tapered ends, hangers rising from the intermediate brackets, a stationary element having a horizontal arm provided with spaced depending hangers, horizontally arranged rails movable between the first-named hangers slightly above the plane of the first-named rails and having inclined tapered ends, and guard rails at opposite sides of the series of first-named rails. 40

45 In testimony whereof I affix my signature in presence of two witnesses.

THOMAS JOSEPH GORMAN.
